UNITED STATES PATENT OFFICE.

RAYMOND NAUTH, OF BUFFALO, NEW YORK.

ELECTRICAL APPARATUS FOR CAUTERIZING OR HEATING BODY TISSUES.

Application filed September 27, 1927. Serial No. 222,253.

This invention relates to electrical apparatus for cauterizing or heating body tissues and more particularly to novel circuit arrangements by which high frequency current is utilized as the cauterizing or heating agent.

An object of the invention is to provide a circuit arrangement for the generation of sustained or undamped high frequency current which is extremely simple in design and operation and capable of maintaining a constant frequency.

A further object is to provide a circuit in which the output current and voltage may be independently regulated over a wide range so as to provide the proper electrical conditions for each patient and by which the patient may be treated without any danger of shock.

In connection with this use of high frequency current, it is particularly desirable that the high frequency oscillations be undamped and that the frequency of the current be constant. If such conditions are not maintained, the patient will be unpleasantly affected by the pulsating current induced by such variations and while the effect is not a serious one, it is obviously a decided advantage if it can be avoided. Furthermore by maintaining these conditions, other advantages are obtained in that a more constant and intense heating effect will be produced, the efficiency of the circuit greatly increased and the operating voltage of the circuit lowered.

All of the above advantages may be realized by the use of a thermionic or vacuum tube for the generation of the high frequency current, the circuit arrangement being such that the plate and grid circuits are inductively coupled with the usual direct connection at ground. With such an arrangement, I have found that the output current may be taken from the grid circuit instead of the plate as is the usual practice in vacuum tube circuits. This result may be accomplished either by directly connecting the patient to a point along the grid circuit (in effect a shunt connection) or in series with the grid circuit or a part thereof.

As stated above, the practice heretofore in vacuum tube circuits has been to obtain the output current from the plate circuit. By taking the output current from the grid circuit, I have found that I can maintain a high efficiency and at the same time obtain

the advantage of eliminating any danger of shocking the patient during the treatment, a serious danger which accompanies the use of the output current from the plate circuit. 60

Another feature to be considered in this type of work is that the circuit should be such as will permit the easy regulation of the output current over a wide range. This is necessary in view of the fact that the resistances of the various body tissues to be treated vary considerably and that the areas to be treated vary, and furthermore, the resistance of the body tissues decreases with increased heat so as to require regulation 70 during the treatment. I have found that the necessary regulation may be satisfactorily obtained by the provision of a variable condenser shunted across the grid coil. A further regulation may, however, be obtained 75 by an adjustable connection between the output current conductor and the grid circuit or by the provision of a condenser in the output circuit.

Embodiments of my invention are illustrated herein, in which:

Figure 1 is a schematic diagram of one form of circuit in which the output current conductor is adjustably connected to the grid circuit. 85

Figure 2 is a schematic diagram in which the output current conductor is connected in series with the grid coil.

Figure 3 is a schematic diagram of a circuit utilizing alternating current supply and 90 which may be connected to operate like any of the above circuits.

The present circuit arrangement essentially comprises a three electrode vacuum tube 1 having its plate and grid circuits inductively coupled through their respective inductances 2 and 3. The plate circuit is connected from the plate of the tube through the inductance 2 and direct current source 4 to a common point or ground 5. The grid circuit is connected from the grid of the tube through the usual fixed condenser 6 and grid leak resistance 7 and inductance 3 to the common point or ground 5. The filament is connected to a heating current source 8, variable resistance 9 and ground 5 in the usual manner.

The output current may be obtained from the above described arrangement by means of a conductor 10 which is adjustably connected to the grid coil as shown in Figure 1. The magnitude of current obtained by such

connection may be regulated by the provision of a condenser 11 shunted across the grid coil. This current may also be regulated by the provision of a condenser 12 in series with the conductor 10. While both condensers may be used a satisfactory regulation can generally be obtained by the use of one only, the arrangement depending on the particular requirements of the case at hand. This arrangement also permits the voltage of the output circuit to be varied by suitably adjusting the point of contact of the conductor 10 with the grid coil 3. The conductor 10 is connected to an electrode 13 which may be either a cauterizing or heating instrument as desired and which is, of course, the instrument applied to the body. While this arrangement will operate with only one conductor, a second conductor 14 may be employed connecting the ground 5 to the body of the patient.

The output current may also be obtained by connecting the body tissues in series with the grid coil as shown in Figure 2. In this case the grid coil circuit is opened and the body tissues placed directly in series therewith. It is also possible to place the body in series with the grid condenser 11 which is used for regulation purposes in this circuit.

Where a comparatively low current is required I preferably use the series connection. If however, a high current is needed, I find that it is more easily obtained by the shunt connection above described. For this reason I preferably make use of the circuit arrangement shown in Figure 3. In this circuit a transformer 15 supplies heating current to the filament through variable resistance 9 and positive potential to the plate through the rectifier 16. This circuit is also provided with a switch 17 which when thrown one way connects the electrode 13 to the adjustable output current conductor 10 along the grid coil, while when thrown the other way, the grid coil circuit is opened and the electrode connected to the open end of the coil to permit the body to be connected in series with the coil. Thus this arrangement permits a quick change from one connection to another. A further feature is that by utilizing alternating current supply, the apparatus may be made portable and the circuit connected to a lamp socket.

The electrode 13 to be employed may be of any of the well known types. For instance, in cauterizing, I employ a needle in which only a small area at the point is exposed and hence an intense burning effect developed while for heating without burning, I may utilize the same type of needle but having a larger area of exposure and consequently a less intense heat. For purposes of claiming I desire to use the term "burning effect" to cover both cases above stated.

The operation of the device is as follows: The circuits are properly energized so as to cause the tube to oscillate in the well known manner, the design of the tube and associated circuits being such as to cause the same to generate undamped oscillations. The frequency of these oscillations may be of any value above the range in which the nervous system of the body is affected. The output current is then regulated by adjusting the condenser 11 or the condenser 12 or the point of contact of the conductor 10 with the grid coil, the adjustment used depending on the circuit employed and the circumstances of the particular case. For observing the value of current obtained, a milli-ammeter 18 should be placed in series with the conductor 10.

Besides cauterizing or heating body tissues I have found that this arrangement may be used to mark hard surfaces, cut glass and other bodies. I have further found that it may be used to cut into the body tissues with such a comparatively small loss of blood as to be in effect a bloodless opera- 90

tion.

Having fully described my invention, I claim:

1. The combination of a vacuum tube circuit for the generation of undamped high frequency current having coupled plate and grid circuits with means for deriving current from the grid circuit and transmitting the derived current to a body to produce a burning effect thereon.

2. The combination of a vacuum tube circuit for the generation of undamped high frequency current having coupled plate and grid circuits with means for regulating the current in the grid circuit and means for deriving current from the grid circuit and transmitting it to a body to produce a burning effect thereon.

3. The combination of a vacuum tube circuit for the generation of undamped high frequency current having coupled plate and grid circuits with means for regulating the current in the grid circuit, means for deriving current from the grid circuit and transmitting it to a body to produce a burning effect thereon and means for regulating the derived current.

4. The combination of a vacuum tube circuit for the generation of undamped high frequency current having inductively coupled plate and grid circuits an electrode connected to the grid circuit and adapted to receive current therefrom and to transmit the current to a body to produce a burning effect thereon.

5. The combination of a vacuum tube circuit for the generation of undamped high frequency current having inductively coupled plate and grid circuits an electrode connected to the grid circuit and in series with

the grid inductance, said electrode being adapted to transmit the current to a body to produce a burning effect thereon and at least a portion of said body being in series with said grid inductance.

6. The combination of a vacuum tube circuit for the generation of undamped high

frequency current having inductively coupled plate and grid circuits with means for deriving current from the grid circuit and cauterizing body tissues with said current. 10

In testimony whereof I hereby affix my signature.

RAYMOND NAUTH.
